FIG. 2

The dominant features of my design reside in the portions illustrated in solid lines.

I claim:

The ornamental design for a lift truck, as shown and described.
